UNITED STATES PATENT OFFICE.

JOSEPH L. MORRIS, OF LAWRENCE, KANSAS.

MOVABLE CASING FOR CONDENSING-COILS OF REFRIGERATOR-CARS.

SPECIFICATION forming part of Letters Patent No. 727,180, dated May 5, 1903.

Application filed August 5, 1902, Serial No. 118,422. (No model.)

To all whom it may concern:

Be it known that I, JOSEPH L. MORRIS, a citizen of the United States, residing at Lawrence, in the county of Douglas and State of Kansas, have invented new and useful Improvements in Movable Casings for Condensing-Coils of Refrigerator-Cars, of which the following is a specification.

My invention relates to movable housings adapted to be employed in connection with atmospheric condensing-coils of ammonia refrigerating apparatus on railway refrigerator-cars.

The present invention relates to an improvement upon a certain previous invention in refrigerator-cars for which I obtained Letters Patent No. 634,583, issued October 10, 1899.

More specifically, the present invention relates to a novel attachment to be applied to the preliminary condensing-coil described in said patent and designated by numeral 54, said coil being located beneath the floor of the car.

The present invention provides a housing which may inclose the sides and bottom of the condensing-coil and, further, provides means for forcing a draft of air along the condensing-coil within said housing for the purpose of reducing the temperature of the ammonia-gas in said coil to approximately that of the atmosphere.

My invention further provides a novel construction for said housing whereby it may be opened up by the moving of a lever when the car is started or about to start, the effect of which is to expose the condensing-coil to the draft of air below the car-body, caused by the motion of the car.

I will proceed to fully describe my invention with reference to the accompanying drawings, in which—

Figure 1 is a bottom plan view of my invention attached to the bottom of a refrigerator-car, a part of the housing and one end of the car being broken away and the housing being closed. Fig. 2 is a side elevation of the invention, showing the blower and engine within the car, the car-floor being partly in section and the near side housing partially broken away. Fig. 3 is an elevation of the air-box looking into its nozzles. Fig. 4 is an enlarged sectional view showing the outside

housing at the sides of the car and one of the adjacent housings and the shifting-gear, the housings being in closed position. Figs. 5 and 6 are elevations of the respective ends of the rack-bar. Fig. 7 is a top plan view of a portion of one of the housings. Fig. 8 is an enlarged plan view of the rack by means of which the housings are shifted.

1 designates the condensing-coil, which consists of a number of runs of pipe connected at their ends by suitable couplings or unions. The apparatus to which the ends of this coil are connected forms no part of this invention, and hence is not represented in the drawings. However, if reference be made to my aforesaid patent it will be observed that the ends of the coil 54 are connected, respectively, to a compressor 30 and to the main condensing-coil 50.

Ammonia-gas at a high initial temperature is circulated through the condensing-coil 1, (shown herein,) and I propose to cool and condense this gas while the car is in motion by the draft of air which will surround the coil; but while the car is at rest such draft will be absent, and in order to continuously reduce the temperature of the gas I provide a blower, a series of nozzles, and a plurality of rockable housings 6, arranged longitudinally just below (or above, as will be apparent) the pipes of the condensing-coil 1.

The coil 1 is supported by hangers 4, secured to the bottom of the car. These hangers depend low enough to permit the housings to clear the usual brake-cylinders, struts, &c., carried beneath the car-body. The pipes of the coil 1 are secured to the bottoms of the hangers 4 by keepers 3, held by screws 2. The coil 1 and its housings occupy only the space between the car-trucks. (Not shown.)

Each housing 6 consists of a trough-shaped length of sheet metal, connected by a suitable number of ribs 7 to a longitudinal rock-shaft 8. All of the rock-shafts 8 pass through journal-openings in the hangers 4. Said rock-shafts extend from end to end of the housings 6. In case an intermediate row of hangers 4 are provided, as shown in Figs. 1 and 2, each housing 6 will be divided to form a gap, the object of which will presently be apparent.

Upon each rock-shaft 8, adjacent to the

power-chamber of the car, is secured a spur-pinion 9. Above said shafts, extending transversely, is a slidable rack-bar 10, the lower edge of which is provided with sets of teeth 12, which engage the pinions 9, respectively. One manner of mounting the rack-bar 10 is by forming longitudinal slots 13 therein, through which pass cap-screws or stud-bolts 14, entering the hangers 4 and having washers interposed between their heads and the face of the rack-bar.

Secured to depending brackets 16 along the respective sides of the car-bottom are two stationary longitudinal lateral housings 17, substantially upright in position. These lateral housings 17 are made of sheet-iron or of any preferred material. Passing through the lower ends of the two rows of brackets are two rock-shafts 18 and 19, respectively. Secured upon each rock-shaft 18 and 19 are a plurality of arms or ribs 20 and 21, to which are secured two movable sheet-metal housings 17', which form continuations of the respective stationary housings 17, secured to the brackets 16. Secured on rock-shaft 18 at the side of the rack-bar 10 is a pinion 22, which is engaged by a rack 24, rigidly secured to the face of the rack-bar. The lengths of the racks 24 and 26 are equal to half the pitch 30 circumferences of the respective pinions, for the reason that when the bottom housings 6 are swung up to their raised positions they have been turned one-half of a full revolution. (See dotted lines.) The lateral movable housings 17' may also be arranged so that they will turn one hundred and eighty degrees in passing from lowered to raised positions, though such an arrangement is not essential, as the length of their throw may 40 be adjusted by the sizes of the pinions 22, 23, by which they are turned.

The rock-shafts 8, 18, and 19 being connected by a virtually-continuous rack 10, if any one of said shafts be rocked the other shafts 45 will turn the same distance at the same time. Secured to the rack-bar 10 is a rack 35. (Shown in plan in Fig. 8, in which two of the hangers 4 are shown in section.) Engaging this rack 35 is a pinion 36, fixed on a vertical shaft 50 27, which passes through the floor of the car into the power-chamber. Secured on shaft 27 is a crank 37, by means of which said shaft may be rotated.

Hung from the bottom of the car by brackets, close to one end of the condensing-coil 1, is a transverse air-box 28, which is provided with a suitable number of nozzles 29, which project above the ends of the bottom housings 6, just below the rock-shafts 8. Within 60 the power-chamber are an engine 30 and a blower 32, driven by the engine either directly, as shown, or through a counter-shaft. An air-trunk 33 connects the outlet of the blower 32 to the air-box 28. Thus when the 65 blower is operated at a high speed a blast of air is conducted into the air-box and issues through the nozzles 29, which may be about

three and one-half inches in diameter. While the blower is being operated, the car is supposed to be stationary or moving very slowly. 70 In this case the crank 37 is turned in the proper direction to lower all of the bottom housings 6 and simultaneously fold in the lateral housings 17'. When in this position, the bottom housings 6 form a practically-continuous bottom wall below the coil 1 and the lower edges of the lateral housings 17' touch the lower edges of the outer bottom housings 6, and thereby complete the inclosure of the condensing-coil. By this means the draft of air 80 issuing from the nozzles 29 is caused to traverse the entire length of the condensing-coil, it being guided by the housings 6, 17, and 17'. This draft is maintained as long as the car is not in motion and may of course be continued after the car has started, if thought necessary to the condensation of the gas in the coil 1.

Having now fully described my invention, what I claim as new, and desire to secure by 90 Letters Patent of the United States, is—

1. The combination with a refrigerator-car of a condensing-coil thereunder, a plurality of rockable housings under said coil, a pair of lateral housings coacting with said rockable housings, and means for causing an artificial current of air to traverse the space surrounding said coil, substantially as described.

2. The combination with a refrigerator-car of a condensing-coil thereunder, a plurality of rockable housings under said coil, a pair of lateral housings coacting with said rockable housings, the lower portion of each lateral housing being movable, means for moving all of said housings simultaneously, and means for causing an artificial current of air to traverse the space surrounding said coil, substantially as described.

3. The combination with a refrigerator-car of a condensing-coil thereunder, a group of rockable housings arranged in parallel relation, under said coil, said housings forming a transversely-continuous housing when in lowered position, a pair of lateral housings 115 at the respective sides of said group of housings, the lower portion of each lateral housing being movable toward or away from the adjacent rockable housing, means for moving all of said housings simultaneously, and 120 means for causing an artificial current of air to traverse the space surrounding the condensing-coil, substantially as described.

4. The combination with a refrigerator-car of hangers secured to the bottom of the car, 125 a condensing-coil supported by said hangers, a plurality of parallel rock-shafts journaled in said hangers, a trough-shaped housing member secured to each rock-shaft, a pair of lateral housings extending from the car-bottom to the outer trough-shaped housings respectively, the lower portion of each lateral housing being mounted on a rock-shaft parallel to the aforesaid rock-shafts, means for 130

turning all of said rock-shafts simultaneously, and means for causing an artificial current of air to traverse the space surrounding the condensing-coil, substantially as described.

5. The combination with a refrigerator-car of hangers secured to the bottom of the car, a condensing-coil supported by said hangers, a plurality of parallel rock-shafts journaled in said hangers, a trough-shaped housing member secured to each rock-shaft, a pair of lateral housings extending from the car-bottom to the outer trough-shaped housings respectively, the lower portion of each lateral housing being mounted on a rock-shaft parallel to the aforesaid rock-shafts, a pinion secured on each of said rock-shafts, a rack transverse to said rock-shafts and engaging all of said pinions, means for simultaneously turning said rock-shafts, and means for causing an artificial current of air to traverse the space surrounding the condensing-coil, substantially as described.

6. The combination with a refrigerator-car of hangers secured to the bottom of the car, a condensing-coil supported by said hangers, a plurality of parallel rock-shafts journaled in said hangers, a trough-shaped housing member secured to each rock-shaft, a pair of lateral housings extending from the car-bottom to the outer trough-shaped housings respectively, the lower portion of each lateral housing being mounted on a rock-shaft parallel to the aforesaid rock-shafts, a pinion secured on each of said rock-shafts, a rack transverse to said rock-shafts and engaging all of said pinions, means for simultaneously turning said rock-shafts, a plurality of nozzles arranged across one end of condensing-coil,

an engine within the car, a blower driven by the engine, and a trunk connecting the blower to all of said nozzles, substantially as described.

7. The combination with a refrigerator-car of a condensing-coil thereunder, a normally closed housing below and at the sides of said coil, said housing being open at one end, the bottom portion of said housing being composed of a plurality of parallel rockable members, rock-shafts supporting said members, means for simultaneously turning all of said rock-shafts, and means for causing an artificial current of air to traverse the space surrounding the condensing-coil substantially as described.

8. The combination with a refrigerator-car of a condensing-coil thereunder, a normally closed housing below and at the sides of said coil, said housing being open at one end, the bottom portion of said housing being composed of a plurality of parallel rockable members, rock-shafts supporting said members, means for simultaneously turning all of said rock-shafts, means for causing an artificial current of air to traverse the space surrounding the condensing-coil, movable side members of said housing, rock-shafts supporting said movable side members, and means for simultaneously turning all of said shafts, substantially as described.

In testimony whereof I affix my signature in the presence of two witnesses.
